UNITED STATES PATENT OFFICE.

MARK MCCOMAS, OF GREENVILLE, TEXAS.

FLUID-PRESSURE BRAKE.

SPECIFICATION forming part of Letters Patent No. 722,128, dated March 3, 1903.

Application filed December 31, 1901. Serial No. 87,979. (No model.)

To all whom it may concern:

Be it known that I, MARK MCCOMAS, a citizen of the United States, residing at Greenville, in the county of Hunt and State of 5 Texas, have invented new and useful Improvements in Fluid - Pressure Brakes, of which the following is a specification.

My invention has relation to new and useful improvements in fluid - pressure brakes 10 particularly adapted for use on railway-trains; and the object of the invention is to provide a simple, durable, and efficient device for controlling the exhaust of fluid under pressure from the brake-cylinder, and 15 thereby preventing such exhaust when the auxiliary pressure is reduced below a predetermined degree and allowing the restoration of the auxiliary-reservoir pressure without the necessity of releasing the brakes.

20 A further object of the invention is to produce a device which will prevent the premature release of the brakes before the auxiliary reservoir has been recharged.

The invention consists in the improved arrangement of the various elements comprising the device and their aggroupment in operative combination, to be more fully described hereinafter and the novelty of which will be particularly pointed out and distinctly 30 claimed.

I have fully and clearly illustrated my invention in the accompanying drawings, wherein—

Figure 1 is a side elevation of a fluid-pressure brake system in connection with which 35 my invention is employed. Fig. 2 is an enlarged vertical longitudinal sectional view of the device, and Fig. 3 is a bottom plan view of the invention.

40 Referring to the drawings, 1 designates a portion of a train-pipe, which is connected in any approved manner to a suitable source of supply and from which projects a branch pipe 2, which is in turn coupled to a triple 45 valve 3, having communication with an auxiliary reservoir 4 and the brake-cylinder 5.

The construction and arrangement of the system just described are practically the same as the Westinghouse form of brake mechanism and needs no further description.

In carrying out my invention I connect a pipe 6 to the exhaust-port 7 of the triple valve

3 and to the exhaust-controlling device, which is secured to the auxiliary reservoir of the fluid-pressure system in any suitable manner. 55

The exhaust-controlling device above referred to and which embodies my invention I designate by the numeral 8. This device comprises a central cylindrical casing 9, the upper portion of which is provided with an 60 annular shoulder 9^a and an annular internally - threaded flange 9^b, which flange and shoulder are adapted to be engaged by a depending or exteriorly - threaded flange a, formed on a cap b, whereby the top portion 65 of the casing 9 is closed. The bottom portion of the casing is also provided with a flange 9^c, which is similar to the flange 9^b and is adapted to receive a vertical exteriorly - threaded flange 9^d, formed on the lower tubular casing 22. 70

The cylindrical casing 9 is divided into upper and lower chambers (designated by 10 and 11, respectively) through the medium of a valve 12, which is adapted to be seated 75 upon a valve-seat 13, arranged intermediate the casing and above the valve 12. Projecting upwardly from the top face of the valve 12 is a vertical stem 14, the extreme upper end of which terminates in a threaded shank 80 14^a for the purpose hereinafter described. The valve 12 is of a lesser diameter than the chamber 11, in which it works, and is surrounded by a plurality of perforations 17, 85 formed in the bottom of the chamber for the escape of the fluid, as will be explained hereinafter.

Resting upon the shoulder 9^a of the cylinder 9 is a diaphragm 28, which is securely held in place on the said shoulder by the 90 flange a and the cap b when the said cap is screwed down in position. At its center the diaphragm is provided with an aperture 28^a, having an annular flange 28^b, and within the said aperture is suitably secured a nut 29, 95 formed with a central threaded aperture adapted to receive the shank 14^a on the stem of the valve, whereby the said diaphragm and valve are operatively coupled. To insure against the displacement of the nut from 100 its position within the diaphragm, a pin 30 is inserted through the flange 28^b of the nut and shank, substantially as shown in the drawings.

From the under face of the valve 12 projects a depending stem 18, which is formed with a reduced portion 19, which forms a shoulder 20, against which bears a spring 21, 5 located within the tubular portion 22 of the casing above referred to. At its lower end the interior of the portion 22 is threaded, as at 22^x, and engaging the said threads and extending up within the interior of the casing 10 is an interiorly-threaded adjusting-nut 31, the upper face of which bears against the spring 21, whereby the tension of the said spring may be regulated. The nut 31 is securely held in position by means of a jam- 15 nut 32, which is threaded upon the nut 31 and engages the lower end of the spring-casing. Of course it will be obvious that the degree of resistance accorded by the valve will be regulated by the predetermined 20 amount of pressure from the brake mechanism.

It will be noticed that the pipe 6 is connected to the casing 9 through a threaded inlet-port 25, positioned intermediate the 25 valve 12 and the diaphragm 28, while the entire device 8 is connected to the auxiliary reservoir through the medium of a threaded neck 26, having a central passage or port 27 therein, which communicates with the chamber 10, as will be presently explained.

In one side of the casing 22 is formed a port 33 for the escape of the air within the same, and on the side of the case 9, containing the valve and the diaphragm, is an exhaust-valve 35 34, whereby pressure between the diaphragm and valve may be relieved.

The operation of the device is as follows: When the auxiliary cylinder is being charged, the fluid under pressure enters the device 40 through the neck 26, and upon the pressure becoming sufficiently high to overcome the spring the valve is moved toward the spring, thereby permitting the air to pass out through perforations 17, forming the exhausts. This 45 position of the valve is maintained so long as the auxiliary cylinder is charged. When the brakes are applied, the pressure is reduced in the auxiliary cylinder and the air will flow out of the port 27 until the pressure that 50 forces the valve in the position above described is equal with that in the auxiliary cylinder. When the pressure is reduced sufficiently to be overcome by the spring 21, the diaphragm and valve 12 will move toward the 55 auxiliary cylinder until the valve is seated on the seat 13. However, when the pistons of the triple valve are moved to released position by increase of train-pipe pressure air

will pass through the exhaust to the triple valve and into the device 8 and will be detained by the valve being seated at 13. It will be held in this position until such time as the auxiliary pressure is great enough to overcome the tension of the spring, thus permitting air to exhaust or pass by the seat 13 60 to the atmosphere through the perforations arranged adjacent the valve. Of course it will be understood that the opening 33 is for the purpose of preventing the pressure in the cylinder 22. 70

Having thus fully described my invention, what I claim, and desire to secure by Letters Patent, is—

1. In a safety device for fluid-pressure brakes, the combination with a casing having 75 an inlet-port communicating with the auxiliary reservoir, an inlet for the exhaust from the triple mechanism, and a relief-valve, said casing being provided with a valve-seat dividing it into upper and lower chambers, the 80 lower of which is provided with exhaust-ports, of a valve intermediate the said chambers and held normally unseated, said valve having a vertically-extending stem having a threaded portion, and a depending stem having a reduced portion to form a shoulder, a spring surrounding the reduced portion and bearing against the shoulder, a nut for controlling the tension of the spring, a diaphragm mounted in the upper chamber and having a central aperture, and an interiorly-threaded nut secured in said aperture to receive the threaded stem on the valve. 85

2. In a safety device for fluid-pressure brakes, the combination with a casing having 90 an inlet-port communicating with the auxiliary reservoir, an inlet for the exhaust from the triple mechanism, and a relief-valve, said casing being provided with a valve-seat dividing it into upper and lower chambers, the 95 lower of which is provided with exhaust-ports, of a valve intermediate the said chambers, said valve having a vertically-extending stem, and a depending stem having a reduced portion to form a shoulder, a spring surrounding 100 the reduced portion and bearing against the shoulder, a nut for controlling the tension of the spring and a diaphragm in the upper chamber, said diaphragm being secured to the vertical stem on the valve. 105

In testimony whereof I affix my signature in presence of two witnesses.

MARK MCCOMAS.
